UNITED STATES PATENT OFFICE.

HENRY MILLER, OF ANN ARBOR, MICHIGAN.

WIRE-TWISTER.

SPECIFICATION forming part of Letters Patent No. 317,832, dated May 12, 1885.

Application filed May 15, 1884. (No model.)

To all whom it may concern:

Be it known that I, HENRY MILLER, a citizen of the United States, residing at Ann Arbor, in the county of Washtenaw and State of Michigan, have invented a new and useful 5 Wire-Twister, of which the following is a specification.

My invention relates to twisters for twisting wires that are stretched to carry pickets in a 10 picket and wire fence, where the said wires are usually stretched in pairs horizontally, secured to vertical posts set in the ground by staples, and retain the pickets in a vertical position by being crossed or twisted between 15 the pickets.

The objects of my invention are as follows: first, to provide a tool that will cross or twist by a complete turn the wires of all the pairs in the fence at one movement; second, to provide a device that will retain these wires securely in the position last named while the 20 picket is fixed in place. I attain these objects by the mechanism illustrated in the accompanying drawings, in which—

Figure 1 is an elevation of the apparatus 25 used, viewed in the direction of the line of the fence from the side the operator stands on to work it. Fig. 2 is a perspective view of the machine in operation, and Fig. 3 is a detail.

A B are two bars carrying a rack-bar at each 30 end of each, set at suitable distances apart on these bars A B, according to the spacing of the pairs of wires. C are two pinions worked by the racks and kept in place in the line of 35 the wires by a plate on each side of each pinion, which are of a size to cover over onto the edges of the racks, and held to the pinions by a central stud passing through them and the pinions, as indicated, or by any equivalent 40 device. The bars A B are held together by an eyebolt, R, which embraces one bar by its properly-shaped eye and passes through the other bar, receiving a crank-nut, N, working on a screw, P, on the end of the bolt and bearing 45 on a washer on the outside of this bar. The eye of the eyebolt may or may not carry a roller, K, against the outside of the bar it embraces, or any other device to facilitate the sliding motion of this bar through the eye 50 when the nut N is tightened. The bars A B

carry each a handle, H, for moving them so as to turn the pinions C, and also a step, D, each, for aiding by the use of the foot of the operator in turning the pinions. The pinions C have holes L through them for the wires to 55 be twisted to pass through, and are slotted so they can be inserted between the wires of a pair, and the said wires readily admitted to these holes L.

My device is used as follows: The nut N being sufficiently screwed off of the screw at P; the pinions C may be removed from between the bars A B. Each wire of a pair is passed through the slots in the pinions C to the holes L. Each pair of wires now carrying a pinion, the bars A B are held in place against the pinions, each pinion standing in the middle of its pair of racks. The nut N is then to be screwed on till the bars A B are pressed sufficiently against the pinions to stand alone 70 in place wherever set with reference to each other by the operator. By placing the foot upon one of the steps D and grasping the handles H, the operator slides one bar past the other, thereby rotating the pinions C and giving the wires of all the pairs the required twist about each other. A picket is then inserted between the wires of each pair, set, and the whole apparatus slid forward on the wires a little as the work runs. The operator now 75 places his foot on the other step D and, grasping the handles H, slides the bars back again, giving the wires a twist in the opposite direction. These movements are repeated at will.

In starting from a post the apparatus is set 80 as in the figure, the wires given a half-turn, after which the pinions will stand at the lower end of one rack and at the upper end of the other, the racks being of a length suitable for giving the pinions a complete turn.

The number of racks and pinions in any case 85 will depend upon the number of pairs of wires in the fence.

What I claim as my invention, and desire to 90 secure by Letters Patent, is—

1. In a wire-twister, the combination, with 95 the rack-bars A B, of the slotted perforated pinion or pinions C, with their slotted and perforated plates L, for retaining them in place on the racks, as shown and described. 100

2. In a wire-twister, the combination of the slotted and perforated plates and pinions C, and the racks and bars A B, with the handles H and steps D, for working the apparatus, as shown and described.
3. In a wire-twister, the combination of the slotted and perforated pinions and plates C, the racks and bars A B, and the handles H and steps D, for working the apparatus, with the clamping device R, as shown and described, to all for the purposes set forth.

HENRY MILLER.
